CONTROL SWITCH

Oscar F. Carlson, Chicago, Ill., assignor, by direct and mesne assignments, of one-half to Oscar F. Carlson Company, Chicago, Ill., a corporation of Illinois, and one-half to Everett N. McDonnell, Chicago, Ill.

Application October 4, 1935, Serial No. 43,564

19 Claims. (Cl. 200—84)

This invention relates to control switches, and more particularly is directed to a control switch responsive to the level of water in a boiler, or to the level of oil in a fuel supply tank for a burner or the like, and also responsive to the development of excessive pressures in the boiler or tank, for actuating an alarm circuit and for cutting off the burner motor or heating means if the pressure condition is not corrected.

10 In the copending application of Alfred W. Shepherd, Serial No. 36,447, filed August 16, 1935, there is disclosed a level control switch corresponding to that of the present invention, and the present invention comprises an extension of the underlying principles of that application to provide a switch capable of responding to both level and pressure.

15 The preferred form of the present invention is directed to a float chamber which may be suitably supported at any desired level, containing a sealed float member having flexible hollow supporting means, with a switch carried within the float and responsive to tilting of the float for controlling operation of any desired electric circuit. 20 The tilting of the float can be accomplished either by lowering of the liquid level, or by predetermined increase in pressure within the float chamber.

25 One object of the present invention is to provide a float controlled switch responsive to both liquid level and pressure.

Another object of the present invention is to provide an adjustable pressure control which in no way influences or interferes with the operation of the switch responsive to liquid level.

30 A further object of the present invention is to provide a control switch structure in which a float completely encloses a switch member, the float being responsive to both pressure and liquid level control, with the switch responding in like manner to both conditions.

35 Other objects and advantages of the present invention will appear more fully from the following detailed description, which, taken in conjunction with the accompanying drawings, will disclose to those skilled in the art the particular construction and operation of a preferred form of the present invention.

40 In the drawings:

Figure 1 is a diagrammatic view showing one manner in which the control switch of the present invention may be employed;

45 Figure 2 is a vertical sectional view through the control switch shown in Figure 1;

Figure 3 is an end elevational view of the switch shown in Figure 2;

Figure 4 is an enlarged sectional view through the pressure adjusting means, taken substantially on line 4—4 of Figure 2;

Figure 5 illustrates a modified form of means rendering the switch mechanism pressure responsive; and

Figure 6 is a section taken at an enlarged scale along the line 6—6 of Figure 5.

Referring now in more detail to the drawings, I have indicated at 5 a heater, such as a boiler or the like, provided with a suitable burner mechanism 6 operated by the motor 7, the burner and motor being supported upon a suitable stand 8. Obviously any desired type of burner mechanism may be employed.

20 The boiler 5 is provided with a gauge glass 9 for indicating the level of water in the boiler compartment, and connected to the lower fitting 10 of the gauge glass is an extending pipe 11 which is connected to the float housing 12. The float housing 12 is also connected through the pipe 13 to a suitable blow-off valve 14 mounted at the upper end of the boiler 5.

25 Considering the detailed construction of the float control switch, the switch structure is, in the main, similar to that shown in the copending Shepherd application above referred to, comprising a housing 16 provided with a tapped opening 17 into which the pipe 13 is connected, and also provided with the tapped opening 18 into which the extension pipe 11 is fitted. The housing 16 is also provided with the tapped outlet 19 to which a suitable drain valve 20 may be connected, if desired.

30 The housing 16 is adapted to be closed at its end by a disc or plate member 20 sealed about the end of the housing by means of the gasket 22. The disc 20 at its central portion is provided with an opening to which is sealed the inner end 23 of a hollow flexible bellows member 24, which has its outer end 25 secured to a plate 26 forming the closure for one end of a float member 27, which at its opposite end is closed by the cap member 28.

35 Disposed within the float 27 is a mercury switch member 29, which is supported in fixed position by means of the clip members 30 connected together through the bracket member 32 and secured on the interior side walls of the float to maintain the switch 29 in fixed position within the float, as clearly shown in Figure 3.

40 The leads for the switch, indicated at 33, extend rearwardly through the interior of the bel-

55

lows 24 outwardly of the disc 20. The disc 20 is clamped to the rear end of the housing 16 by means of a clamping plate having a channel faced annular ring portion 34, and provided with 5 a plurality of clamping screws 35. Supported on the plate is an insulating disc 36, carrying suitable bushings 37 to which the ends of the leads 33 are connected through metal contact clips 31. These bushings 37 are adapted to receive suitable 10 terminal lugs 38 and terminal screws 39 for securing conductors thereto to lead the circuit outwardly of the switch.

The terminal lugs 38 are formed from metal stampings having inturned ends 40 adapted to 15 seat in suitable recesses formed in a second insulating disc 42. A suitable separator 43 is interposed between the opposed pairs of lugs.

Enclosing the terminal plates 36 and 42 is a 20 metal closure member 44 forming an outlet box 45 at the rear end of the switch housing, and which is provided with a cylindrically flanged portion 46 engaging the peripheral edge of the plate 20. The member 44 is secured to the housing 16 by means of a plurality of screws 47 passing 25 through the flange 46. A suitable closure plate 48 is secured to the housing 44 by means of the screw 49 and provides a rectangular box at the rear end defining the chamber 45. A suitable opening 50 is provided for leading out 30 the cable or conduit containing the conductors connected to the respective terminal screws 39.

The operation of the control switch as described up to this point corresponds to the operation of the switch shown in the copending Shepard application, that is, upon lowering of the float 27 due to lowering of level within the float chamber 16, the float tends to rotate about the bellows 24, flexing the bellows, until the reinforcing ring 52 of the float engages the integral stop 40 53 formed in the housing 16. At this time, the switch 28 operates to close an alarm circuit, to shut off a burner motor, or to perform any similar function, such as opening a feed water control valve or the like.

45 The present invention particularly resides in the provision of a tapped opening 54 provided in the upper surface of the housing 16, which is adapted to receive the threaded bushing 55, the bushing 55 carrying a regulating pin 56, which 50 pin is provided at its upper end with a collar or flange portion 57 limiting its downward movement with respect to the bushing 55, and with a head 58 having a suitable kerf 59 formed therein for receiving a screw driver or similar 55 member for rotating the pin 56. A suitable cap nut 60 threads over the upper end of the bushing to enclose the head 58 of the pin 56, preventing accidental movement of the pin, and the engagement of this cap nut with the flange 57 60 of the pin seals the pin by engagement against the upper surface of the bushing 55, preventing leakage therefrom.

The lower end of the pin 56 extends into the interior of the housing 16 and is provided with 65 an annular grooved portion 62 receiving the eccentric ring member 63 which is adapted to have abutting engagement with the rear edge of the float 27, as indicated at 64. This engagement is shown in more detail in Figure 4. By 70 rotating the pin 56, it will be apparent that the outer periphery of the disc 63 will move toward and away from the rear edge of the float 27, whereby upon increase of pressure within the housing 16 the bellows 24 will be compressed, 75 moving the rear edge of the float into abutting

engagement with the ring 63, as indicated at 64.

Further movement of the upper end of the float is thereby prevented, and upon further increase of pressure the float rocks downwardly in the same manner as when the level of liquid 5 within the chamber is reduced. Thus, upon predetermined increase of pressure, the float rocks about the point of engagement 64 with the pin in a downward direction to produce actuation of the switch 29. The adjustment of the pin 56 10 will produce operation of the float at any predetermined pressure, by providing a predetermined movement of the float before the engagement of the rear edge thereof with the disc 63. 15

Considering now the circuit shown in Figure 1, a transformer 65 is provided, the secondary of which is connected through one conductor 66 to one electrode within the mercury tube switch 29 supported in the float 27. The other conductor of the secondary winding of the transformer 65 is connected to the burner motor and to one side of a control circuit for an alarm device 67. The other electrode of the switch 29 is connected through the conductors 68 and 69 to the 25 burner motor and the control circuit for the alarm device, respectively.

The control circuit for the alarm device comprises a conductor 69 having a relay 70 in the circuit thereof, which relay is adapted to normally maintain the circuit through the alarm device unenergized, but upon deenergization of the circuit through the relay 70 the armature 72 thereof drops down to close the circuit through the alarm device, thereby actuating the 35 alarm. At the same time the motor is shut off.

Thus, if the water level in the boiler drops 40 below a predetermined point, the alarm device is sounded and the burner motor is shut off. Also, if the pressure within the boiler builds up beyond a predetermined point, the alarm device is sounded and the burner motor is shut off. It is therefore apparent that I have provided a control switch which may be operated either by variations in level of water in a boiler or the like, 45 or by variation in the pressure to which the switch is subjected, thus preventing operation of the burner motor under low water or high pressure conditions, and which simultaneously is capable of actuating an alarm to indicate the presence of a dangerous condition. 50

By virtue of the adjustable means described above, the float controlled switch is rendered responsive to pressure within the housing 16. In Figures 5 and 6 I have illustrated another means 55 for securing the same result, embodying a separate pressure responsive bellows 80 mounted exteriorly of the housing 16 on a fitting 81 adapted to be threaded into the casing opening 54. The pressure responsive bellows 80 is sealed at its 60 lower margin to the fitting 81 and has its interior in communication with the interior of the float housing 16 through a central opening 82 in the fitting or bushing 81. The bellows 80 includes a sealed head in the form of a rigid plate 85 to 65 which a bracket 86 is secured interiorly of the bellows.

A forked member 90 is pivotally connected at its upper end to the bracket 86, and the lower bifurcated end of the member 90 includes arm 70 sections 91 partially embracing the bellows 24, being disposed on opposite sides thereof and carrying suitable pivots 92 or the like on which rollers 93 are rotatably mounted. The rollers 93 bear against a rectangular plate member or flange 94 75

secured to the bellows end of the float 27, and a pair of thrust links 97 and 98 are mounted on the pivots 92 and at their other ends are pivotally anchored to brackets 88 secured to or carried by a plate 100.

In its generic aspects, the operation of the above means rendering the float 27 responsive to pressure is substantially the same as that set forth above in connection with Figures 1 to 4. Since the bellows 80 is in communication with the steam space of the float housing 16, the bellows expands and contracts in response to pressure changes. For example, at or below the desired normal pressure, the member 90 stands at the position indicated in Figure 5 with the rollers 93 substantially at the center of the plate 94 and the float 27. In this position the pressure within the casing 16 reacts through the links 97 and 98 directly against the plate 100, but does not tilt the float, the bellows 24 being relieved thereby of any tendency to become collapsed. However, the connection between the member 90 and the float 27 is such that the rocking of the latter in response to liquid level changes, is not interfered with, and hence the unit remains fully responsive to the water level in the housing 16. When the pressure within the housing or casing 16 becomes abnormally high, the bellows 80 is expanded, the head 85 moving upwardly and carrying with it the member 90. The upward movement of the latter carries the rollers 93 above the center of the plate 94, and as soon as the rollers 93 move thus into an eccentric position the pressure within the casing 16 immediately becomes effective to rock the float 27 downwardly in substantially the same manner that the interior pressure acts in the construction shown in Figure 2 to tilt the float so as to operate the switch means enclosed therein. Since the bellows 80 moves to different positions in response to different pressures within the casing 16, the unit shown in Figure 5 is quite sensitive in that the greater the abnormal pressure, the more quickly will the float 27 be tilted, due principally to the greater eccentricity of the rollers 93. Since the bellows 80 forms the pressure sensitive means, the sealing bellows 24 can be made very flexible. If desired, suitable biasing means, such as a spring, may be employed with the bellows 80, and if such spring means, or the bellows, is made adjustable, the unit may be arranged so as to provide for the float 27 tilting at various pressures.

Having described my invention in accordance with the patent statutes, what I claim as new and desire to secure by Letters Patent is:

1. In combination, a float chamber, a float therein, a flexible bellows supporting said float for both pivotal and axial movement in said chamber, a switch in said float having leads extending outwardly of said chamber through said bellows, and means serving as an abutment adapted to be engaged by the float in eccentric relation so that upon collapsing of said bellows due to pressure in said chamber said float is moved into switch actuating position.

2. In combination, a float chamber, a float therein, a flexible bellows supporting said float for movement in said chamber, a switch in said float having leads extending outwardly of said chamber through said bellows, and a member engaged by said float in eccentric relation upon the attainment of a predetermined pressure in said chamber for collapsing said bellows and rocking said float about its point of contact with

said member so as to move said float into switch actuating position.

3. In combination, a float chamber, a float therein, a flexible bellows supporting said float for tilting and axial movement in said chamber, abutment means normally reacting against the central portion of said float for preventing axial movement of the latter while providing for the tilting movement of the float, pressure responsive means for eccentrically shifting said point of reaction so as to cause the pressure within said chamber to tilt said float and control means disposed to be operated in response to changes in position of said float.

4. In combination, a float chamber, a float therein, a flexible bellows supporting said float for movement in said chamber, a switch in said float having leads extending outwardly of said chamber through said bellows, and an adjustable member disposed to be eccentrically engaged by said float upon collapsing of said bellows due to pressure in said chamber for cocking said float into switch-actuating position.

5. In combination, a float chamber, a hollow float therein supported by a flexible bellows member and adapted to flex said bellows during variations in liquid level in said chamber, a mercury switch supported in said float and having terminal connections extending outwardly of said chamber through said bellows, and means disposed to be eccentrically engaged by said float upon predetermined increase in pressure within said chamber for cocking said float into switch-actuating position.

6. In combination, in a float chamber having an apertured disc sealed to one side thereof, a flexible bellows sealed in said aperture and extending into said chamber, a hollow float sealed to and communicating with the interior of said bellows, a gravity operated switch in said float having terminal connections extending outwardly through said bellows and disc, and means disposed to be eccentrically engaged by said float upon predetermined increase of pressure within said chamber for cocking said float into switch-actuating position.

7. The combination with a float chamber having a sealed hollow float therein supported by a flexible bellows, and a gravity-operated switch in said float, of means for operating said float into switch-actuating position upon increase of pressure in said chamber comprising an abutment member projecting into said chamber and disposed to be eccentrically engaged by said float upon said increase of pressure to cock said float out of normal position.

8. The combination with a float chamber having a sealed hollow float therein supported by a flexible bellows, and a gravity-operated switch in said float, of means for operating said float into switch-actuating position upon increase of pressure in said chamber comprising an abutment member projecting into said chamber and disposed to be eccentrically engaged by said float upon said increase of pressure to cock said float out of normal position, said means having a portion projecting out of said chamber for adjusting the pressure at which said float will be operated.

9. A float chamber having an opening in one side wall thereof, a flexible bellows supported at one end within said opening, a float secured to the opposite end of said bellows and communicating with the interior thereof, a switch supported within said float and actuated by tilting of said float due to lowering of liquid level in

said chamber, and means for tilting said float independently of said liquid level upon a predetermined increase of pressure in said chamber.

10. A float chamber having an opening in one side wall thereof, a flexible bellows member projecting into said chamber through said opening, a float supported on the inner end of said bellows, a gravity-operated switch in said float, a pin projecting into said chamber adjacent the inner end of said bellows, and an eccentric disc carried by said pin and disposed to be eccentrically engaged by said float upon collapse of said bellows for tilting said float into switch-actuating position.

15. 11. A float chamber having an opening in the top wall thereof, a bushing in said opening, a pin extending through said bushing into said chamber, a float in said chamber having a gravity-operated switch therein, flexible pressure responsive means supporting said float from the side wall of said chamber, and means on said pin eccentrically engaging a portion of said float upon contraction of said pressure responsive means for tilting said float into switch actuating position.

12. The combination with a float chamber of the class described including a float having an expansible and contractible support for allowing tilting of said float upon lowering of liquid level 30 in said chamber, of means disposed to eccentrically react on said float for effecting corresponding tilting thereof upon contraction of said support under a predetermined pressure and control means disposed to be operated in response to changes in position of said float.

13. The combination with a hollow float member having a flexible supporting bellows at one end thereof and adapted to tilt about said bellows in response to variations in liquid level, said bellows being contractible under increases in pressure, of means eccentrically engaging a portion of said float as said bellows contracts for tilting said float about said bellows and control means disposed to be operated in response to 45 changes in position of said float.

14. In a float chamber, a float member having a flexible hollow support in one side wall of said member, and means for limiting horizontal movement of said float in said chamber comprising a pin extending into said chamber, cam means at the inner end of said pin for engaging a vertically extending portion of said float to prevent lateral movement thereof, means at the outer end of said pin providing for adjustment 50 of said cam means and control means disposed to be operated in response to changes in position of said float.

15. In combination, a float chamber, a float

therein, a flexible bellows supporting said float for angular movement in a vertical direction in said chamber, a switch in said float having leads extending outwardly of said chamber through said bellows, an adjustable member adapted to engage said float in one position so as to resist any axial movement of said float, and a bellows operatively connected with said member and responsive to the pressure within said chamber for moving said member into a position rendering the pressure within said chamber effective to rock said float into switch actuating position.

16. A combined liquid level and pressure responsive device comprising a float chamber, a float movably mounted therein, a flexible bellows operatively connecting said float with said chamber for both axial and vertical angular movement, switch mechanism mounted on the interior of said float and actuated by the angular position of the latter, and a pressure sensitive unit responsive to the pressure within said float chamber and eccentrically reacting at a point against said float so that upon the occurrence of a predetermined pressure within said float chamber said float rocks about said point of reaction to 25 actuate said switch mechanism.

17. A liquid level and pressure responsive device comprising, in combination, a float chamber disposed to be connected to a container of a liquid under pressure, a float in said chamber, means for effecting the rotation of said float about different centers in response to change in level or pressure of said liquid, and electric switch means carried by said float and disposed to be operated in response to change in position thereof.

18. A liquid level and pressure responsive device comprising, in combination, a float chamber disposed to be connected to a container of a liquid under pressure, a float in said chamber, means for effecting the rotation of said float about one axis 40 in response to change in level of said liquid, means for effecting the rotation of said float about another axis in response to change in pressure, and control means disposed to be operated in response to change in position of said float caused 45 either by change in level or pressure.

19. A liquid level and pressure responsive device comprising, in combination, a float chamber disposed to be connected to a container of a liquid under pressure, a float in said chamber, 50 means for effecting the rotation of said float about one axis in response to change in level of said liquid, means for effecting the rotation of said float about another axis in response to change in pressure, and electric switch means carried by 55 said float and disposed to be operated in response to change in position thereof.

OSCAR F. CARLSON.
